16 Claims.

(Cl. 74—60)

This invention relates to mechanism for the interconversion of reciprocation and rotation for engines, pumps, and compressors, of the class having cylinders parallel to the shaft, the class commonly called barrel type, axial, circle, or round engine mechanisms.

In describing such mechanisms, the terms "swashplate" and "wobbleplate" or "wabbler" have been used indiscriminately for plate structures inclined to the shaft and operably connecting the reciprocating parts to the shaft. A "swashplate" has been defined as rotating with the shaft, and a "wabbler" as nonrotating, but this may be illogical. Confusion may be avoided by using other terms. Herein a plate inclined to and rotating with the shaft is called by Michell's term, "slant," while a plate structure mounted on bearings on and inclined to the shaft, is called a "connecting plate" or "conplate," since it serves to operably connect reciprocating parts to the shaft, analogous to the "connecting rods" or "conrods" in a crank mechanism. An object of this invention is to provide improved means for predetermining correctly the motion of a conplate.

In discussing round engine mechanisms, it is also convenient to shorten "reciprocating members" to "recipers," the term describing the parts or the assemblies whose motion is predominantly reciprocation along cylinder axes. A recipers may be a simple piston, but more often it is a more comprehensive structure and may include a crosshead portion and one or two piston portions.

In most of the conplate mechanisms, the torque reaction from the shaft is on the conplate which must therefore be held against rotation by substantial means. But the true motion of the conplate is three-dimensional—a point on its mid-plane describes a spherical lemniscate, appearing in end view to rotate about a small circle at twice shaft speed and in the same sense. It is almost if not quite impossible to provide a conplate restraint capable of carrying the engine torque reaction while maintaining correct conplate motion. Any restraint which interferes with the true motion of the conplate, introduces serious vibrations and abnormal stresses. For example, if one part of the conplate is confined to move in a plane, the inertia effects and extraordinary stresses introduced can destroy the mechanism. Objects of this invention are to avoid such difficulties by providing a conplate mechanism of such construction that, while the conplate transmits the turning effort from the recipers to the shaft, the conplate itself is practically free from torque; and further by providing simple and practical control means for confining the conplate motion to that which is natural and geometrically correct.

Briefly described, the invention comprises a

conplate mechanism in which the operable connection between each recipers and the shaft includes a wristpin fastened to the conplate arm with the axis of the pin substantially tangent to a circle concentric with and in the plane of the conplate. All working surfaces of the conplate being surfaces of revolution relative to the conplate axis, or tangent thereto, practically no torque can be exerted on the conplate by the coaxing parts, neglecting friction. The invention consists further of forming the ends of each wristpin substantially spherical and of providing internal surfaces in each recipers correctly formed to coact with the ends of the wristpins so that, together, they predetermine the conplate motion and maintain it geometrically correct.

In the drawings, Fig. 1 is an end view, partly in section, of a circle mechanism showing a true projection of the conplate in its inclined position on the shaft; Fig. 2 is a longitudinal section of the mechanism taken on the line 2—2 of Fig. 1; Fig. 3 is a sectional view of the recipers and associated parts, taken on the line 3—3 of Fig. 2; and Fig. 4 is an analysis of the mechanism.

Referring to the drawings, shaft 10 is mounted for rotation in bearings 14 in cylinder blocks 15. Slant members 16 are suitably keyed and fastened to shaft 10, and conplate 11 is operably mounted between slants 16, the coaxing bearing surfaces being spherical as shown, altho it is evident that any suitable bearing construction may be used for mounting conplate 11 on shaft 10 so long as conplate 11 is operable upon shaft 10 and inclined thereto with the conplate and shaft axes intersecting substantially in the mid-plane of conplate 11.

Conplate 11 has as many arms as there are recipers 17. Each of the recipers 17 comprises one or two piston portions 17b and a crosshead portion 17c. Pistons 17b are operable in cylinders, formed in blocks 15, and crossheads 17c are operable in cylindrical crosshead guides coaxial with the cylinders and formed in casing 12. The fixed parts of the machine, cylinder blocks 15 and casing 12, are held together by bolts 13.

The operable connection between each recipers 17 and the arm of conplate 11 includes wristpin 18, the axis of wristpin 18 being substantially tangent to a circle concentric with and in the plane of the conplate. The radius of the circle, the conplate arm radius, is such that the center of wristpin 18, during its normal movement, travels the same distance inside and outside the cylinder axis, i. e. the wristpin center is the same distance inside the cylinder axis when the recipers is on center as shown in Fig. 2, as it would be outside the cylinder axis if the recipers were at mid-stroke.

Associated with wristpin 18 is pinhead 20 which is operable in a bore thru crosshead 17c, the axis of this bore being perpendicular to that of wristpin 18. Formerly the wristpin was fixed in or otherwise axially immovable relative to the pinhead in order to obtain the largest possible wristpin bearing area, the bearing being in the conplate arm. According to the present invention, the wristpin is adjustably fastened to the conplate arm, as by setscrew 19, but the bearing area need be no smaller because the wristpin is longer, being permitted to extend on one side or the other of pinhead 20 by reliefs cut thru the wall of the bore in crosshead 17c. Wristpin ends 18e are formed substantially spherical, and internal surfaces 17e may be essentially cylindrical or spheroidal to coact properly with wristpin ends 18e to maintain the motion of conplate 11 always geometrically correct.

Wristpins 18 are axially adjustable relative to the arms of conplate 11 to permit them to accommodate errors in indexing of the several cylinders or crosshead guides or of the arms of conplate 11. During assembly, one only of wristpins 18 may be secured by its setscrew 19, the other wristpins 18 being set snugly enough to stay where they are left by contacts with surfaces 17e while the mechanism is turned over. When each wristpin 18 is correctly adjusted axially relative to its arm of conplate 11, all wristpins 18 are securely locked in correct position as by setscrews 19.

In operation, rotation of shaft 10 and slants 16 causes conplate 11 to change the position of its plane without rotation of conplate 11 relative to its own axis or the fixed parts 15 and 12 of the machine. The motion of wristpin 18 relative to the bore in pinhead 20, and of pinhead 20 relative to the bore in crosshead 17c, is in each case a combination of rotation and axial sliding. The 40 conplate arm center which is the center of wristpin 18 moves in a path describing a lemniscate on the surface of a sphere, which path, in end view, is circular, so that the ends 18e of wristpins 18 can contact successively surfaces 17e of recipers 17. As shown at F and G in Fig. 1, opposite ends 18e of two wristpins 18 are always (neglecting working clearance) in opposite contact with corresponding internal surfaces 17e of two recipers, so that conplate 11 cannot rotate in either direction. For clockwise rotation of shaft 10 in Fig. 1, contact G is well begun, contact F is approaching its end, contact H is about to start, ready to take over the duty of contact F, and contact K has recently passed its job to contact G. Each contact (or working proximity) occurs twice during each revolution of shaft 10; with five arms on conplate 11, there are twenty control contacts between wristpin ends 18e and internal ricer surfaces 17e during each revolution of shaft 10.

While each wristpin 18 constantly changes its angular relationship to the corresponding ricer 17, if wristpin ends 18e are spherical about the center of wristpin 18, and control surfaces 17e are cylindrical over their length where contact occurs, the contacts will always be in the plane normal to the ricer axis whatever the angularity of wristpin 18. This construction is the simplest to understand and is mathematically correct. Other more involved surfaces may be used to obtain somewhat broader contact than the point contact between a sphere and a cylinder of somewhat larger radius, altho the loading in 70 75

this case is low because the conplate is practically free from torque.

To understand how little torque is on the conplate with this mechanism, and in general to understand the operation of the mechanism more completely, and especially how ends 18e of wristpins 18 coact with internal surfaces 17e to predetermine correctly the motion of conplate 11 and to maintain it geometrically correct, reference is had to the analysis of Fig. 4.

Conplate mechanism analysis

In Fig. 4:
origin 0=center of conplate at intersection of shaft and conplate axes

x-axis=shaft axis

y-axis=vertical axis

z-axis=transverse axis, the only line in the conplate plane and 1 shaft axis

n=no. of conplate arms

S=reciper stroke

h=cyl. circle radius

r="little circle" radius

b=(h+r)=conplate arm radius

a=.5S=2 $\sqrt{hr}$ because $(h+r)^2=a^2+(h-r)^2$

ϕ =conplate angle

$$\sin \phi = \frac{a}{b} = \frac{2\sqrt{hr}}{(h+r)}$$

$$\cos \phi = \frac{(h-r)}{(h+r)}$$

θ =reference angle of shaft rotation

=0 when the reciper is at mid-stroke, when the z-axis intersects the reciper axis.

$\frac{d\theta}{dt}=\omega$ radians/sec. angular velocity of the shaft.

Views I, II, and III are the familiar end view, longitudinal section, and top or radial view, respectively, and correspond to Figs. 1, 2, and 3 of the drawings.

Correct conplate motion is readily understood 45 by plotting the locus of a point in the conplate plane during operation of the mechanism. An easy way to plot three views of the locus of the conplate arm or wristpin center is to start with the conplate normal to the shaft, a position it never occupies in the mechanism, but one that is easy to draw. If the conplate were normal to the shaft, a circle of radius $\overline{OA_0}$ in end view I, would contain all conplate arm centers A_0 ; and in view II, the conplate would be represented by the y-axis. Divide the circle in end view I into a convenient number of equal sectors, project the points A_0 to the y-axis of view II, and swing the conplate into its actual position by rotating its angle ϕ about the z-axis. Points A_0 in end view I will move vertically toward the z-axis, while their projections in view II swing thru arcs, and when projected back to view I, intersect the vertical lines at the points A.

The points A in end view I all fall on a true ellipse, the end view of the conplate circle when the conplate is in its actual position inclined to the shaft. If the mechanism were running, the conditions shown at the several positions in view I would appear successively in any one position, generating the end view of the "locus" as shown for the top cylinder position in view I. This end view of the "locus" of conplate arm center A is a "little circle" of radius r , and the point A goes around the "little circle" at twice shaft speed.

From each point A in end view I, draw $\overline{AQ} \perp \overline{OA_0}$. $\overline{OQ}$ is the y -coordinate of the point A and can be used to plot the elevation of the "locus" of A in view II.

$\overline{AQ}$ is the z -coordinate of the point A and can be used to plot the top view of the "locus" of A in view III.

The coordinates of conplate arm center A are:

$$\begin{aligned} x_A &= (h+r) \sin \theta \sin \phi = 2\sqrt{hr} \sin \theta = a \sin \theta & 10 \\ y_A &= h+r \cos 2\theta \\ z_A &= r \sin 2\theta = 2r \sin \theta \cos \theta \end{aligned}$$

From the foregoing, it is clear that movement of the point A out of the plane of the cylinder and shaft axes during operation, is due to the inclination of the conplate, a constant quantity, and not to any rotation of the conplate about its own axis. Rotation of the conplate about its own axis cannot be tolerated in a conplate mechanism because it would have to be oscillatory and would involve polar inertia effects difficult to handle. The essential characteristic of correct conplate motion is complete freedom from rotation of the conplate relative to its own axis and to the fixed parts of the machine. The conplate must also be

$$\frac{d^2x_J}{dt^2} = -a\omega^2 \sin \theta \left[1 + \frac{a^2 - 2b^2 + 3b^2 \cos^2 \theta - a^2 \cos^4 \theta}{2(b^2 - a^2 \cos^2 \theta)^3} \right]$$

free from inertia torque, wherefore it must be in static and dynamic balance relative to its axis.

In the mechanism as shown in Figs. 1, 2, and 3, it is now more clear how ends 18e of wristpins 18, spherical about conplate arm centers A, coact with surfaces 17e, properly formed in recipers 17, to confine the motions of points A to their respective "little circles," thereby insuring correct conplate motion.

The three views of the "locus" of the conplate arm center A refer to the top cylinder position in view I. To find conditions at any angle θ of shaft rotation, start again with the conplate normal to the shaft, and draw $\overline{OA_0}$ at another cylinder position, $\angle \theta$ being the angle thru which the z -axis has rotated bodily with the shaft, since it coincided with $\overline{OA_0}$. Draw wristpin axis $\overline{V_0U_0} \perp \overline{OA_0}$ and extend it to meet the z -axis at Z. Project the points A_0 , V_0 , and U_0 to the y -axis of view II and give the conplate its inclination ϕ as before, locating the lines $\overline{VAU}$ in views I and II, the projections of the wristpin axis in its actual position for $\angle \theta$ as shown. In view I, $\overline{VU}$ extended must also intersect the z -axis at Z. $\overline{A_0A}$ extended intersects the z -axis at M. $\angle A_0CA = 2\theta$. Projection $\overline{OA}$ makes an angle of deviation, $\angle COA = \angle \psi$ with trace $\overline{CO}$ of the plane of the cylinder and shaft axes.

In the mechanism, the pinhead axis always intersects the cylinder axis at right angles and is therefore parallel to the $y-z$ plane and shows true length in view I. The pinhead axis also intersects the wristpin axis at right angles, and will therefore appear $\perp \overline{VU}$ in view I. Draw pinhead axis $\overline{CJ} \perp \overline{VU}$ at J and making $\angle \gamma$ with trace $\overline{CO}$ of the plane of the cylinder and shaft axes. $\angle \gamma$ measures recipers rotation.

By orthographic projection, wristpin axis $\overline{VU}$ and points A and J upon it, may now be shown in views II and III, and the axis C of the particular cylinder now being considered can also be located in views II and III.

The displacement of the recipers from mid-stroke where $\theta=0$, is the same as that of the pin-

head axis, $x_C=x_J$. From views I and II: $x_J = (AM + AJ \sin \beta) \tan \phi$

$$AM = (h-r) \sin \theta$$

$$AJ = AC \cos \angle CAJ = r \cos (\theta - \beta)$$

$$\sin \beta = \frac{AM}{ZA} = \frac{(h-r) \cos \theta}{\sqrt{(h+r)^2 - 4hr \cos^2 \theta}}$$

$$\cos \beta = \frac{ZM}{ZA} = \frac{(h+r) \sin \theta}{\sqrt{(h+r)^2 - 4hr \cos^2 \theta}}$$

Substituting and simplifying, the axial "displacement" of the recipers from mid-stroke position,

$$\begin{aligned} x_J &= 2\sqrt{hr} \sin \theta \left[1 + \frac{2hr \cos^2 \theta}{(h+r)^2 - 4hr \cos^2 \theta} \right] \\ &= a \sin \theta \left[1 + \frac{a^2 \cos^2 \theta}{2(b^2 - a^2 \cos^2 \theta)} \right] \end{aligned}$$

The "velocity" of the recipers,

$$\frac{dx_J}{dt} = a\omega \cos \theta \left[1 + \frac{a^2 - 2b^2 + 3b^2 \cos^2 \theta - a^2 \cos^4 \theta}{2(b^2 - a^2 \cos^2 \theta)^2} \right]$$

The "acceleration" of the recipers,

$$\frac{d^2x_J}{dt^2} = -a\omega^2 \sin \theta \left[1 + \frac{a^2 - 2b^2 + (9b^4 - 6a^2b^2) \cos^2 \theta - 2a^2b^2 \cos^4 \theta + a^4 \cos^6 \theta}{2(b^2 - a^2 \cos^2 \theta)^3} \right]$$

In each of the foregoing expressions for recipers 30 "displacement" from mid-stroke, "velocity," and "acceleration," the first term is harmonic, and the second term defines the deviation from harmonic. For any given ratio, b/a , corresponding to a given conplate angle ϕ , both b and a are eliminated from the second term of each of the three expressions, leaving them much simplified. These expressions hold only for the conplate mechanism having wristpins tangent to the conplate circle and correctly predetermined conplate motion.

If the axial movement of the recipers were harmonic, the axially directed inertia forces of n recipers, each the product of its effective reciprocating mass m and its acceleration, would combine to form an inertia couple about the z -axis of magnitude:

$$M_z = -5nmha \omega^2$$

Actually, because the recipers motion departs slightly from harmonic, the magnitude is about 1.4% larger, but it is within .001% of being constant for any given shaft speed, so that it can be balanced by counterweights capable of producing an equal and opposite centrifugal couple, in a well-known manner, the dynamic balance of this conplate mechanism being practically as perfect as that of the Michell slant-slipper mechanism.

60 In addition to axial movement, the recipers in the conplate mechanism has a little oscillatory rotation, tending to maintain piston rings free.

The angle of deviation of the conplate arm radius from the plane of the cylinder and shaft axes,

$$\angle \psi = \angle COA$$

$$\sin \psi = \frac{AQ}{OA} = \frac{2r \sin \theta \cos \theta}{\sqrt{(h+r)^2 - 4hr \sin^2 \theta}}$$

$$\cos \psi = \frac{OQ}{OA} = \frac{(h+r) - 2r \sin^2 \theta}{\sqrt{(h+r)^2 - 4hr \sin^2 \theta}}$$

The angle of reciprocating rotation.

$$\angle \gamma = \angle OCJ = \angle A_a ZJ$$

$$= \frac{\pi}{2} - \theta - \beta$$

$$\sin \gamma = \frac{2r \sin \theta \cos \theta}{\sqrt{(h+r)^2 - 4hr \cos^2 \theta}}$$

$$\cos \gamma = \frac{(h+r) - 2r \cos^2 \theta}{\sqrt{(h+r)^2 - 4hr \cos^2 \theta}}$$

The reciprocating rotates against shaft rotation while passing mid-stroke; and the reciprocating rotates with shaft rotation while going over center.

The angular velocity of the reciprocating.

$$\frac{d\gamma}{dt} = \omega \frac{2r(h+r) + 4hr \cos^2 \theta}{(h+r)^2 - 4hr \cos^2 \theta}$$

By solving

$$\frac{d\gamma}{dt} = 0, \theta = \arccos \sqrt{\frac{(h+r)}{2h}}$$

when γ is maximum, and

$$\gamma_{max} = \arcsin \frac{r}{h}$$

The angular acceleration of the reciprocating.

$$\frac{d^2\gamma}{dt^2} = \omega^2 \frac{-4hr(h^2 - r^2) \sin 2\theta}{[(h+r)^2 - 4hr \cos^2 \theta]^2}$$

The inertia torque of the reciprocating.

$$T_i = (\text{polar moment of inertia of reciprocating}) \times (\text{angular acceleration of reciprocating})$$

$$= \frac{WK^2}{386} \frac{-4hr(h^2 - r^2) \sin 2\theta}{[(h+r)^2 - 4hr \cos^2 \theta]^2} \text{lb. in.}$$

(all dimensions in inches; $g = 386 \text{ in./sec.}^2$)

$W = \text{wght. of reciprocating}$

$K = \text{radius of gyration of reciprocating}$

As in any piston machine, the resultant reciprocating thrust is the sum of reciprocating inertia and cylinder pressure. By plotting the indicator card of the machine, and the reciprocating inertia derived from the expression for reciprocating acceleration already given, the resultant reciprocating thrust P can be plotted.

To show how the resultant reciprocating thrust P produces torque on the shaft and on the conplate, the auxiliary view IV is drawn on a plane $\perp$ pinhead axis. Since this plane is parallel to both wristpin and cylinder axes, view IV shows the true length of the wristpin and its true position relative to the axis of the cylinder and crosshead. Projections from the end view I to auxiliary view IV must be made $\perp$ $\overline{V'U'}$ and parallel to pinhead axis $\overline{CJ}$ in end view I.

With center at A' and radius $A_a V_0$, arcs intersect projections from V and U at V' and U' respectively. $\overline{V'U'}$ intersects projection from C and J of view I at J' = end view of pinhead axis.

In view IV the trace of the $y-z$ plane intersects wristpin $\overline{V'U'}$ extended, at Z' so that $\overline{ZZ'}$ is parallel to $\overline{JJ'}$. x_A and x_J are the same respectively in both views II and IV.

The projection from O in view I intersects the trace of the $y-z$ plane in view IV at O' . Since view IV is parallel to the wristpin axis, the projection of conplate radius $\overline{O'A'}$ in view IV must

be $\perp \overline{V'U'}$, and must intersect the trace of the $y-z$ plane at O . The $\angle OO'A = \alpha$

$$\tan \alpha = \frac{x_A}{ZA} = \frac{2\sqrt{hr} \cos \theta}{\sqrt{(h+r)^2 - 4hr \cos^2 \theta}} = \frac{a \cos \theta}{\sqrt{b^2 - a^2 \cos^2 \theta}}$$

$$\sin \alpha = \frac{a \cos \theta}{b}$$

$$10 \sec \alpha = \frac{b}{\sqrt{b^2 - a^2 \cos^2 \theta}}$$

Since view IV is parallel to the cylinder axis, the resultant reciprocating thrust P can be shown as a vector applied to the pinhead axis at J' . The component of P normal to the wristpin, $P \sec \alpha$, is applied to the conplate and causes the loading on the conplate bearings. The component $P \tan \alpha$ defines the turning effort and is equal to the torque reaction of the reciprocating crosshead against its cylindrical guide.

View V is drawn on a plane $\perp$ wristpin axis $\overline{V'U'}$. All projections from view IV to view V are made parallel to $\overline{V'U'}$. Points A' and J' are the same in view V. Conplate radius $\overline{O'A'}$ is parallel to the plane of view V and therefore shows its true length. With center at A' in view V, and radius $\overline{OA_0} = b = (h+r)$, the projection in V of O' in view IV is intersected at O' in view V, defining the angle ϵ .

$$30 \sin \epsilon = \frac{x_A \sec \alpha}{(h+r)} = \frac{2\sqrt{hr} \sin \theta}{\sqrt{(h+r)^2 - 4hr \cos^2 \theta}}$$

$$35 \cos \epsilon = \frac{h-r}{\sqrt{(h+r)^2 - 4hr \cos^2 \theta}}$$

The torque on the shaft arising from resultant reciprocating thrust P is equal to the torque reaction of the crosshead upon its cylindrical guide:

$$40 T_s = P \tan \alpha \cdot (h+r) \cos \epsilon + P \tan \alpha \cdot \overline{CJ} = P \tan \alpha \cdot h \cos \gamma$$

$$= Pa \cos \theta \frac{2hb - a^2 \cos^2 \theta}{2(b^2 - a^2 \cos^2 \theta)} = Pa \cos \theta$$

if the fraction be neglected, the value of the fraction being always very nearly 1, varying from

$$\frac{h}{(h-r)} \text{ to } \frac{h}{(h+r)}$$

To find the torque on the conplate, arising from resultant reciprocating thrust P , view VI is drawn parallel to the plane of the conplate. For convenience in interpretation of view VI, it is repeated at the left of Fig. 4 in correct relationship to view II. The force component in the conplate plane, tending to turn the conplate about its axis, is the component parallel to the conplate radius $\overline{O'A'}$.

$$P \sec \alpha \sin \epsilon$$

60 and its moment arm is $\overline{A'J'}$ from view IV. The torque on the conplate

$$T_r = P \frac{4hr\sqrt{hr}(h+r)^2 \sin^2 \theta \cos \theta}{[(h+r)^2 - 4hr \cos^2 \theta]^2} =$$

$$65 Pa \cos \theta \frac{a^2 b^2 \sin^2 \theta}{2(b^2 - a^2 \cos^2 \theta)^2}$$

The torque on the conplate is always small, as can be seen from the ratio of torque on the conplate to torque on the shaft:

$$T_r = \frac{Pa \cos \theta a^2 b^2 \sin^2 \theta}{Pa \cos \theta (2hb - a^2 \cos^2 \theta) (b^2 - a^2 \cos^2 \theta)} = .000 \text{ to } .054 = .025$$

75 in summation in a mechanism of usual proportions

tion with the conplate angle, $\phi=18^{\circ}93$. With any reasonable proportion, the torque on the conplate from reciprocating thrust can never be more than 5% of the torque on the shaft.

When the components producing torque on the conplate act inwardly, as shown in view VI, they tend to center the conplate. When these components act outwardly, they tend to uncenter the conplate and would make its motion unstable and its operation noisy if no control of the conplate motion were provided. The inwardly acting components predominate whenever the summation of cylinder pressures is greater than that of the reciprocating inertia forces. Thus when a conplate engine is running normally under load, the inwardly-acting components, tending to center the conplate, would permit it to run quietly even if no conplate control were provided. However, when reciprocating inertia forces are greater in summation than the cylinder pressures, as when the shaft overruns the reciprocators, the outwardly-acting components predominate, and control of the conplate motion is necessary.

In providing a conplate mechanism in which the conplate is practically free from torque, together with simple and practical control means for maintaining the conplate motion geometrically correct, as shown and described, it is apparent that the objects of this invention as stated have been attained. While a particular construction has been illustrated, it is understood that changes in the construction and in the arrangement of the mechanism may be made without departing from the spirit or scope of the invention as set forth in the following claims.

I claim:

1. In a machine of the class described, a shaft, reciprocators reciprocable parallel thereto, and mechanism operably connecting said shaft and said reciprocators, said mechanism including a conplate operably mounted on and inclined to said shaft, wristpins adjustably fastened to said conplate with their axes substantially tangent to a circle in the plane of and concentric with said conplate, pinheads operably connecting said wristpins and said reciprocators, and surfaces in and substantially coaxial with said reciprocators coaxing with the ends of said wristpins to control the motion of said conplate.

2. In a machine of the class described, a shaft, reciprocators reciprocable parallel thereto, and mechanism operably connecting said shaft and said reciprocators, said mechanism including a conplate operably mounted on and inclined to said shaft, an arm on said conplate for each of said reciprocators, a wristpin fastened to each of said arms with its axis substantially tangent to a circle in the plane of and concentric with said conplate, a pinhead and a bore in said pinhead operably receiving said wristpin, another bore in each of said reciprocators operably receiving said pinhead, the axes of said bores being perpendicular to each other, and means for maintaining the motion of said conplate geometrically correct, said means including the ends of said wristpins and surfaces in said reciprocators operably coaxing therewith.

3. In a machine of the class described, a shaft, reciprocators reciprocable parallel thereto, and mechanism operably connecting said shaft and said reciprocators, said mechanism including a conplate operably mounted on and inclined to said shaft, an arm on said conplate for each of said reciprocators, a wristpin fastened to each of said arms with its axis substantially tangent to a circle in the plane

of and concentric with said conplate, means operably connecting said wristpins and said reciprocators, and means for predeterminedly determining the geometrically correct movement of said conplate and including surfaces substantially coaxial with said reciprocators and coaxing with the ends of said wristpins.

4. In a machine of the class described, a shaft, a frame and bearings in said frame operably supporting said shaft, cylinders in said frame parallel to said shaft, reciprocators reciprocable in said cylinders, and mechanism operably connecting said shaft and said reciprocators, said mechanism including a conplate operably mounted on and inclined to said shaft, wristpins securely fastened to said conplate with their axes substantially tangent to a circle in the plane of and concentric with said conplate, and means coaxing with the ends of said wristpins for maintaining the motion of said conplate geometrically correct.

5. In a machine of the class described, a shaft, a frame and bearings in said frame operably supporting said shaft, cylindrical crosshead guides in said frame and parallel to said shaft, reciprocators including crosshead portions reciprocable in said cylindrical crosshead guides, and mechanism operably connecting said shaft and said reciprocators, said mechanism including a conplate operably mounted on and inclined to said shaft, wristpins securely fastened to said conplate with their axes substantially tangent to a circle in the plane of and concentric with said conplate, means operably connecting said wristpins and said crosshead portions of said reciprocators, and surfaces in said crosshead portions coaxing with the ends of said wristpins for maintaining the motion of said conplate geometrically correct.

6. In a machine of the class described, a shaft, reciprocators reciprocable parallel thereto, and mechanism operably connecting said shaft and said reciprocators, said mechanism including a conplate operably mounted on and inclined to said shaft, wristpins with their axes substantially tangent to a circle in the plane of and concentric with said conplate, and means associated with said wristpins for maintaining the motion of said conplate such that the locus of a point on the conplate circle is defined by the coordinates:

$$\begin{aligned} x_A &= a \sin \theta \\ y_A &= h + r \cos 2\theta \\ z_A &= r \sin 2\theta \end{aligned}$$

the several quantities as defined in the specification.

7. In a machine of the class described, a shaft, reciprocators reciprocable parallel thereto, and mechanism operably connecting said shaft and said reciprocators, said mechanism including a conplate operably mounted on and inclined to said shaft, wristpins securely fastened to said conplate with their axes substantially tangent to a circle in the plane of and concentric with said conplate, and means for defining the motion of said reciprocators so that the displacement of each reciprocator from mid-stroke position is:

$$x_r = a \sin \theta \left[1 + \frac{a^2}{2} \frac{\cos^2 \theta}{(b^2 - a^2 \cos^2 \theta)} \right]$$

the several quantities as defined in the specification.

8. In a machine of the class described, a shaft, reciprocators reciprocable parallel thereto, and mechanism operably connecting said shaft and said reciprocators, said mechanism including a conplate operably mounted on and inclined to said shaft, wristpins fastened to said conplate with their

axes substantially tangent to a circle in the plane of and concentric with said coplate, and means for defining the motion of said recipers so that the velocity of each recipor is:

$$\frac{dx_J}{dt} = aw \cos \theta \left\{ 1 + \frac{a^2 - 2b^2 + 3b^2 \cos^2 \theta - a^2 \cos^4 \theta}{2(b^2 - a^2 \cos^2 \theta)^2} \right\}$$

the several quantities as defined in the specification.

9. In a machine of the class described, a shaft, recipers reciprocable parallel thereto, and mechanism operably connecting said shaft and said recipers, said mechanism including a coplate operably mounted on and inclined to said shaft, wristpins with their axes substantially tangent to a circle in the plane of and concentric with said coplate, and means associated with said wristpins for defining the motion of said recipers so that the acceleration of each recipor is:

$$\frac{d^2x_J}{dt^2} = -aw^2 \sin \theta \left\{ 1 + \frac{a^2 - 2b^2 + (9b^4 - 6a^2b^2) \cos^2 \theta - 2a^2b^2 \cos^4 \theta + a^4 \cos^6 \theta}{2(b^2 - a^2 \cos^2 \theta)^3} \right\}$$

the several quantities as defined in the specification.

10. In a machine of the class described, a shaft, recipers reciprocable parallel thereto, and mechanism operably connecting said shaft and said recipers, said mechanism including a coplate operably mounted on and inclined to said shaft, and operable connections between said coplate and said recipers so constructed and arranged that the motion of said coplate is predetermined and the torque on said coplate arising from recipor thrust P is:

$$T_r = Pa \cos \theta \frac{a^2b^2 \sin^2 \theta}{2(b^2 - a^2 \cos^2 \theta)^2}$$

the several quantities as defined in the specification.

11. In a machine of the class described, a shaft, recipers reciprocable parallel thereto, and mechanism operably connecting said shaft and said recipers, said mechanism including a coplate operably mounted on and inclined to said shaft, and operable connections between said coplate and said recipers so constructed and arranged that the motion of said coplate is predetermined and the ratio of the torque on said coplate arising from recipor thrust P and the torque on said shaft arising from recipor thrust P is:

$$\frac{T_r}{T_s} = \frac{a^2b^2 \sin^2 \theta}{(2hb - a^2 \cos^2 \theta)(b^2 - a^2 \cos^2 \theta)} \leq$$

5% in summation

the several quantities as defined in the specification.

12. A rocker mechanism comprising a shaft, a coplate operably mounted on and inclined to said shaft, recipers reciprocable parallel to said shaft, and operable connections between each recipor and said coplate, said operable connections each including a wristpin fastened to said coplate with its axis substantially tangent to a circle concentric with and in the plane of said coplate, all working surfaces of said coplate assembly being surfaces of revolution relative to the coplate axis or tangent thereto, excepting only the ends of said wristpins, said ends being substantially spherical, and internal surfaces substantially coaxial with said recipers and coacting with said spherical wristpin ends to predetermine the coplate motion and maintain it geometrically correct.

13. In a machine of the class described, a shaft, a frame and bearings therein operably supporting said shaft, cylinders disposed about and parallel to said shaft, cylindrical crosshead guides coaxial with said cylinders, recipers including piston portions and crosshead portions operable in said cylinders and crosshead guides respectively, and mechanism operably connecting the crosshead portions of said recipers with said shaft, said mechanism including a coplate operably mounted on and inclined to said shaft and a coplate arm assembly operably connecting said coplate with each of said crosshead portions of said recipers, said assembly including working surfaces essentially tangential to circles parallel to the plane of said coplate (thereby avoiding direct application of working loads to produce torque on said coplate), and control surfaces substantially radial to the plane of said coplate, at least two

of said control surfaces being always in working proximity to two of said recipers (to prevent rotation of said coplate relative to said frame and to maintain the motion of said coplate geometrically correct).

14. In a machine of the class described, a shaft, a frame and bearings therein operably supporting said shaft, cylinders disposed about and parallel to said shaft, recipers operable in said cylinders, and mechanism operably connecting said recipers to said shaft, said mechanism comprising a coplate assembly including a coplate operably mounted on and inclined to said shaft, working surfaces in said assembly substantially tangent to circles parallel to the plane of said assembly (thereby avoiding direct application of working loads to produce torque on said coplate), and control surfaces in said assembly substantially radial to the plane of said coplate and contacting said recipers successively (to prevent rotation of said coplate relative to said frame and to maintain the motion of said coplate geometrically correct).

15. In a machine of the class described, a shaft, a frame and bearings therein operably supporting said shaft, cylindrical surfaces in said frame disposed about and parallel to said shaft, recipers operable in said cylindrical surfaces, a coplate operably mounted on and inclined to said shaft, arms on said coplate, and means operably connecting said arms with said recipers and including attachments on said arms, at least two of said attachments being always in opposite working proximity to two of said recipers to prevent rotation of said coplate relative to said frame and to maintain the motion of said coplate geometrically correct.

16. In mechanism of the class described, a shaft, a coplate operably mounted on said shaft and inclined thereto, reciprocating members operable parallel to said shaft, and means operably connecting each of said reciprocating members with said coplate, said means including an arm on said coplate, a wristpin with its axis held substantially tangential to a circle concentric with and in the plane of said coplate, said wristpin operably engaging said reciprocating members during operation, and means for adjusting said wristpin axially and for locking said wristpin securely upon said arm.

EDWIN S. HALL.

Certificate of Correction

Patent No. 2,303,838.

December 1, 1942.

EDWIN S. HALL.

It is hereby certified that errors appear in the printed specification of the above numbered patent requiring correction as follows: Page 2, second column, line 59, for "its" read *it*; page 4, second column, line 2, in the equation, for " $\angle OO'A$ " read $\angle OO'A'$; page 5, first column, line 50, claim 1, for "swashplate" read *conplate*; page 6, first column, line 57, claim 12, for "rocker" read *conplate*; and in the drawings, Sheet 2, Figure 4, upper left-hand corner thereof, for "COMPLATE AXIS" read *CONPLATE AXIS*; and that the said Letters Patent should be read with these corrections therein that the same may conform to the record of the case in the Patent Office.

Signed and sealed this 1st day of June, A. D. 1943.

[SEAL]

HENRY VAN ARSDALE,
Acting Commissioner of Patents.
